US0D1043120S

(12) **United States Design Patent** (10) Patent No.: **US D1,043,120 S**
(45) Date of Patent: ** Sep. 24, 2024

(54) **STORAGE BOX**

(71) Applicant: **Guangzhou Starknight Trading Co., Ltd.**, Guangzhou (CN)

(72) Inventors: **Weifeng Huang**, Guangzhou (CN); **Li Chen**, Guangzhou (CN)

(**) Term: **15 Years**

(21) Appl. No.: **35/518,569**

(22) Filed: **Sep. 20, 2023**

(80) **Hague Agreement Data**

Int. Filing Date: **Sep. 20, 2023**

Int. Reg. No.: **DM/231850**

Int. Reg. Date: **Sep. 20, 2023**

Int. Reg. Pub. Date: **Oct. 6, 2023**

(51) LOC (14) Cl. **03-01**

(52) U.S. Cl.

USPC **D3/294**; D12/423
